(76) Inventor: **Ki Yong Chang**, Seoul (KR)

(57) **CLAIM**

(**) Term: **14 Years**

The ornamental design for a hand operated air pump for traction device for orthopedic purpose, as shown and described.

(21) Appl. No.: **29/400,330**

(22) Filed: **Aug. 26, 2011**

(30) **Foreign Application Priority Data**

DESCRIPTION

Jun. 2, 2011 (KR) 30-2011-0022645

(51) **LOC (9) Cl.** **15-02**

(52) **U.S. Cl.** **D15/7**

(58) **Field of Classification Search** D15/7-9;

FIG. 1 is a front perspective view of a hand operated air pump for traction device for orthopedic purpose;
FIG. 2 is a front elevation view of the hand operated air pump for traction device for orthopedic purpose of FIG. 1;
FIG. 3 is a rear elevation view of the hand operated air pump for traction device for orthopedic purpose of FIG. 1;
FIG. 4 is a left side view of the hand operated air pump for traction device for orthopedic purpose of FIG. 1;
FIG. 5 is a right side view of the hand operated air pump for traction device for orthopedic purpose of FIG. 1;
FIG. 6 is a top plan view of the hand operated air pump for traction device for orthopedic purpose of FIG. 1;
FIG. 7 is a bottom plan view of the hand operated air pump for traction device for orthopedic purpose of FIG. 1; and,
FIG. 8 is another front perspective view of the hand operated air pump for traction device for orthopedic purpose of FIG. 1 in actual use with its cylinder pulled down for air pumping.
